188,533

BODY FOR A GOLFER'S VEHICLE OR THE LIKE

Raymond L. Nimmo, 3316 Hamilton St., and Wess A. Culwell, 600 E. Roberts St., both of Fort Worth, Tex.

Filed May 20, 1959, Ser. No. 55,990

Term of patent 14 years

(Cl. D14—3)

Fig. 1

Figure 1 is a perspective view taken from the front and one side of a body for a golfer's vehicle or the like, embodying our new design; and

We claim:

The ornamental design for a body for a golfer's vehicle or the like, substantially as shown.
